CLAIM

The ornamental design for a cookware vessel body, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top, side perspective view of a cookware vessel body, showing my new design;

FIG. 2 is a right side elevation view thereof, the left side being a mirror image thereof;

FIG. 3 is a front elevation thereof, the rear being a mirror image thereof;

FIG. 4 is a top plan view thereof;

FIG. 5 is a bottom plan view thereof; and,

FIG. 6 is a bottom, side perspective view thereof.

Portions of the claimed design that include the color black and dark shades of grey are illustrated with intermittent white lines to indicate the surface curvature of these portions.

Portions of the claimed design that are not colored or in lighter colors than black and dark shades of grey are illustrated with intermittent black lines to indicate the surface curvature of these portions.

The broken line showing of the handles in FIGS. 1-6 depicts environment and forms no part of the claimed design. The long-short broken lines on the handles depict the boundary of the claim and form no part of the claimed design.
